UNITED STATES PATENT OFFICE.

EDWIN L. WHITE, OF BROOKLYN, NEW YORK, ASSIGNOR TO J. H. WHITE MANUFACTURING CO., OF BROOKLYN, NEW YORK, A CORPORATION OF NEW YORK.

DESIGN FOR AN EXTENSION-PLATE.

44,429.

Specification for Design.

Patented July 29, 1913.

Application filed May 29, 1913. Serial No. 770,802. Term of patent 7 years.

To all whom it may concern:

Be it known that I, EDWIN L. WHITE, a citizen of the United States, residing at the borough of Brooklyn, in the county of Kings and State of New York, have invented a new, original, and ornamental Design for an Extension-Plate, of which the following is a specification, reference being had to the accompanying drawing, forming part thereof.

Figure 1 is a plan view of an extension plate, showing my new design, and Fig. 2 is a side elevation of the same.

I claim:

The ornamental design for an extension plate, as shown.

EDWIN L. WHITE.

Witnesses:

A. H. MOWEN,
CHAS. SCHARFMAN.
